UNITED STATES PATENT OFFICE.

ROBERT O. HAMMOND, OF FARMINGDALE, NEW YORK, ASSIGNOR, BY MESNE ASSIGNMENTS, TO TYWACANA FARMS POULTRY COMPANY, OF FARMINGDALE, NEW YORK, A CORPORATION OF NEW YORK.

EGG-MAILING CASE.

1,102,191.

Specification of Letters Patent.

Patented June 30, 1914.

Application filed December 30, 1912. Serial No. 739,331.

To all whom it may concern:

Be it known that I, ROBERT O. HAMMOND, a citizen of the United States, resident of Farmingdale, in the county of Nassau and State of New York, have made a certain new and useful Invention in Egg Mailing Cases; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the invention. Fig. 2 is a transverse vertical section of the same. Fig. 3 is a detail perspective view of the outer part of the box. Fig. 4 is a similar view of the inner part of the box. Fig. 5 is a similar view of the intermediate part of the box.

The invention has relation to egg mailing cases of paper board, and it consists in the novel construction and combinations of parts, as hereinafter set forth.

In the accompanying drawings illustrating the invention, the numeral 1 designates an open-end slidable cover or outer member; 2 an open-top and open-bottom rectangular frame or intermediate member, and 3 an inner member formed of a flat piece of paper board having a bottom 4, upturned plane ends 5, and inturned rectangular top flaps 6 meeting at their inner ends, said inner member being located preferably within the frame 2, so that the upturned ends 5 will be held up by the ends of said frame when the members 2 and 3 are withdrawn or slid endwise from the cover, the bottom 4 in the withdrawn position of the members closing the frame 2 at the bottom, and the upturned ends and top flaps serving to keep the bottom in place. The construction described will also provide two plies or thicknesses of paper board upon each side of the box.

Fitting within the rectangular frame and inner member are a plurality of comparatively short upright tubes or cylinders 7 also of paper board, and designed each to contain one egg, said tubes extending at their ends adjacent to the top flaps and bottom of the inner member, and the outer of the

tubes extending at their sides adjacent to the sides of the rectangular frame and the upturned ends of the inner member. Each 55 tube has at each end a disk cover 8, fitting within the tube, a cushion 9 of some suitable material such as sheet cotton wool, of larger dimensions or diameter than the tube being first placed over the end of the tube and the 60 disk cover pressed in place to compress the marginal portion of the cushion within the tube end between the edge of the disk and the side walls of the tube, the marginal portion of the cushion having projection outward at 10, beyond the end of the tube, laterally outward at 11, over and under the ends of the tube between said ends and the bottom 4 or the top flaps 6, and inward at 12, between the adjacent tubes and between 70 the outer of the tubes and the sides of the frame 2, and the upturned ends of the member 3.

It is preferred to make each member of the box of a single flat sheet of paper board, 75 the two outer members or parts being provided with laps 13 and 14, glued to the bodies thereof, and the upright tubes having each a lap joint, glued together.

What I claim is:—

80 A paper-board box, comprising an open-top and open-bottom continuous-wall rectangular intermediate frame, an inner part having a bottom, upturned end walls and inturned top flaps, said bottom and said flaps closing said frame at top and bottom and the end walls of said frame being located without and in bracing engagement with and upholding said upturned ends of the inner part to form a container, and an open-end rectangular continuous-wall cover part having telescoping engagement with said container, whereby when the container is partially withdrawn from said cover part one top flap may be turned back for access 95 to the contents, the container being held in form.

In testimony whereof I affix my signature, in presence of two witnesses.

ROBERT O. HAMMOND.

Witnesses:

GEORGE M. ANDERSON,
STUART HILDER.
